UNITED STATES PATENT OFFICE.

WILLIAM S. SCARLETT, OF FALL RIVER, MASSACHUSETTS.

SAFETY DEVICE FOR SHIPS.

1,016,781.

Specification of Letters Patent.

Patented Feb. 6, 1912.

Application filed May 25, 1911. Serial No. 629,456.

To all whom it may concern:

Be it known that I, WILLIAM S. SCARLETT, citizen of the United States, residing at Fall River, Massachusetts, have invented 5 certain new and useful Improvements in Safety Devices for Ships, of which the following is a specification.

My invention aims to provide a safety device for use on ships for the expeditious 10 handling of passengers from the ship to the boats without danger of loss of life or injury to the passengers.

As is well known it is a difficult thing to control passengers in times of danger or 15 panic on ships, and many injuries result, and some times loss of life from filling the boats with passengers before lowering the same and after lowering partially or wholly it is difficult to transfer the passengers from 20 the ship to the boat particularly in cases of women and children.

My invention has for its object a safety device which will quickly and without 25 danger transfer the passenger or passengers from any deck of the vessel to the boat. The device is also adapted to allow the passengers to be transported to step into it with the greatest ease; to be handled with 30 perfect safety between the vessel and the boat and to collapse in the boat so as to permit of the ready and safe exit of the passengers.

In the accompanying drawing, the figure shows the side of a vessel having three 35 decks; with a boat hanging from the davits and the safety conveyer ready for use. The vessel indicated will of course represent any ship or steamer. For convenience three decks are shown.

40 The ordinary davits are indicated at A, having between them a connecting cable B. The boat C may be of any ordinary or improved construction and is connected to the davits by the usual blocks and tackle shown 45 at D. The davits and cable B are held by stays *a* which have detachable connections at *b*. Supported on the cable B by a pulley

or eye *c*; is a block *d* between which and the block *e* plays a rope *f* controlled by a line having detachable connection *g*. The block 50 *e* supports in turn a safety conveyer *E* which is composed of double canvas or a like flexible fabric having a wooden or other ring in its bottom to keep it distended, while at its upper edge is provided a ring 55 *h* to which ropes or flexible supports *i* are connected with the block *e* through the ring *h*. I aim to make the safety conveyer *E* so that when pressure is released, as when the conveyer rests upon the deck of the ship 60 the conveyer will collapse so that the passengers to be conveyed will step into the interior over the edge and then when pressure is applied through the controlling rope *f*, the walls of the conveyer will be elevated 65 around the passengers to be conveyed and the passengers may occupy a standing position, holding the stays *i* as the conveyer is lowered into the boat or other place of safety. The construction of the conveyer 70 easily allows four passengers, one to each space between the stays *i*, but it will of course be understood that the conveyer may be made of larger size to hold more than four if desired. As the conveyer is lowered 75 into the boat *C* the passengers are protected from injury and from falling, and as the conveyer comes in contact with the boat its walls collapse and allow the passengers to step out into the boat without 80 difficulty.

I do not limit myself wholly to the use of the safety conveyer in connection with a boat as I may use it upon a single davit to lower passengers or to take up passengers. 85

What I claim is:

1. A safety apparatus for loading passengers into boats comprising a pair of davits with a block and tackle at each davit for connection with the ends of the boat, 90 a collapsible safety conveyer and means intermediate the davits and independent of the block and tackle thereof for lowering the safety conveyer into the boat as held

by the block and tackle of the davits, substantially as described.

2. In combination in apparatus of the class described, a pair of davits each with a block and tackle, a cable extending between the davits, a safety conveyer of collapsible form and a block and tackle suspended from the cross cable for manipu-

lating the safety conveyer, substantially as described.

In testimony whereof, I affix my signature in presence of two witnesses.

WILLIAM S. SCARLETT.

Witnesses:

WALTER HORTON,

WILLIAM E. SULLIVAN, Jr.
